DRAFTING INSTRUMENT

Filed Oct. 6, 1947

UNITED STATES PATENT OFFICE

2,594,193

DRAFTING INSTRUMENT

Bram Mendes, New Rochelle, N. Y.

Application October 6, 1947, Serial No. 778,252

2 Claims. (Cl. 33—26)

1

It is among the objects of this invention to provide a combination drafting instrument especially for use by school children or amateur draftsmen, which combines the functions of a beam compass, T-square and ruler, yet which is inexpensive in cost, small in size, light in weight and rugged in construction, requiring but little skill in the manipulation thereof and which readily can be adapted for use for any of its intended purposes without the need for tools or complicated adjustments.

According to the invention, these objects are accomplished by the arrangement and combination of elements hereinafter described and more particularly recited in the claims.

In the accompanying drawings in which are shown one or more of various possible embodiments of the several features of the invention,

Fig. 1 is a perspective view of the drafting instrument.

Fig. 2 is a transverse sectional view on a larger scale, taken along line 2—2 of Fig. 1.

Fig. 3 is a longitudinal sectional view, taken along line 3—3 of Fig. 1.

Fig. 4 is a view similar to Fig. 2, taken along line 4—4 of Fig. 1, and

Fig. 5 is a view similar to Fig. 4 with the bracket pivoted 180 degrees.

Referring now to the drawings, the device comprises a beam or ruler 11 preferably having a plurality of longitudinal slots 12 therethrough equally spaced from each other and extending nearly the entire length thereof.

Affixed to the underside of the beam 11 at each end thereof as by screws 13, are blocks 14 and 15, respectively, which serve to space the beam from the surface on which it is to be used.

A rectangular cross bar 16, of greater thickness than that of blocks 14 and 15, is detachably affixed to one of said blocks, illustratively block 14, by means of a tongue 17 unitary with said block and extending laterally therefrom which fits in a corresponding groove or recess 18 in the side 19 of the cross bar. A set screw 20 threaded into a corresponding opening 21 in the cross bar engages said tongue as at 21, rigidly to retain the cross bar 16 at right angles to the beam 11 to form a T-square.

A carriage, which in the embodiment herein comprises a slide member 22, is mounted on the beam so as to be slidably movable thereon, the depending sides 23 of the slide member straddling the longitudinal edges 11' of the beam and being bent thereunder as at 24. The slide mem-

2

ber which is substantially U-shaped is preferably of resilient material such as spring sheet metal and the cross piece 25' thereof which lies transversely across the upper face of said beam is bowed as at 25 so that the sides 23 thereof resiliently grip the edges 11' of the beam securely to retain the carriage in any desired location on the beam 11. The carriage is provided with a plurality of openings 26 therein aligned with the longitudinal slots 12 in the beam. Each opening is provided with a holder 26' which frictionally retains a marking instrument 27 such as a pencil or pen, inserted in said holder for the purpose hereinafter set forth.

15 A substantially U-shaped bracket 28 having arms 29 which straddle the sides 30 of one of said aforementioned blocks, illustratively block 15, is pivotally mounted thereon by transverse pivot pin 28'. The bracket on the exposed underside of its cross piece 31 joining the arms 29, has a centering point or pivot 32 otherwise affixed thereon, which serves as the center of an arc or circle when the device is used as a compass.

20 The arms 29 of the bracket are of such length that the bracket may be pivoted 180 degrees from the position in which the device is used as a compass, as shown in Fig. 5, to the position shown in Fig. 4. In this latter position pivot 32 extends upwardly and so does not interfere with the stable support of the device upon the surface on which it is used. In order that the bracket may be rigidly affixed in either of the above two positions, detents are provided in the form of embossments 34, preferably two in number, on the inner face of each of the arms 29. The embossments, which are equidistant from the pivot pin 28' around which the bracket is rotated, coact with corresponding depressions 35, one on each side 30 of block 15 and one on each edge 11' of beam 11 both when the bracket is in compass position, as in Fig. 5, and when it is pivoted 180 degrees therefrom to idle position as in Fig. 4.

25 As the T-square attachment or cross bar 16 can readily be removed from the beam 11, the drafting instrument may conveniently be carried in a small carrying case. If it is desired to draw several parallel lines simultaneously, a marking device 27 may be inserted into each of the holders 26' and through the corresponding opening 26 in slide member 22 and the longitudinal slot 12 in the beam 11, and then by sliding the slide member 22 along the beam, which is placed over the surface to be marked, such parallel lines may conveniently be drawn. The position on

beam 11 of slide member 22 may be adjusted by merely pressing on the bowed portion 25' thereof, thereby spreading the sides 23 so that they no longer grip the edges 11' of beam 11 and thus permitting free movement of the slide member, the sides 23 re-gripping the beam upon manual release of the bowed portion 25'.

For use of the device as a beam compass, the U-shaped bracket 28 is pivoted so that the center point 32 thereof may press against the surface to be marked. With a pencil inserted in one of the holders 26' of said slide member, the beam may be rotated about its axis or center point 32 to inscribe a circle of the desired radius.

For use of the device as a T-square, the tongue 17 of block 14 is merely inserted into the grooved recess 18, in cross bar 16 and the set screw 20 tightened.

It is of course apparent that the device may be used as a conventional ruler by using the beam alone, and for this purpose appropriate scale markings, as shown, are along the edge or edges thereof.

It is thus seen that the invention affords a neat, compact and highly efficient multi-purpose or combination drafting instrument, especially useful for school children or amateur draftsmen, which may quickly be set for any of its intended functions, and which is especially compact for storage when the T-square head is removed.

As many changes could be made in the above construction and many apparently different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A drafting instrument for inscribing lines on a surface, said instrument comprising a beam having a plurality of longitudinal slots therethrough extending nearly the entire length thereof, a pair of blocks respectively affixed on the underside of said beam at each end thereof to

space said beam from such surface, a carriage slidably mounted on said beam, said carriage having means for removable support of a plurality of inscribing devices to extend through said longitudinal slots respectively and contact such surface, a substantially U-shaped bracket having a center point thereon, the arms of said bracket straddling one of said blocks and said beam and being pivotally affixed thereto so as to be movable through an arc of 180 degrees whereby when said bracket is rotated about its pivot to bring said center point into contact with such surface, said beam may be rotated about said center point and a cross bar removably affixed to one of said blocks at right angles to said beam.

2. The combination set forth on claim 1 in which said arms each have embossments on the inner face thereof which coact with corresponding depressions on said one block and said beam rigidly to hold said bracket in its extreme positions of rotation.

BRAM MENDES.
